UNITED STATES PATENT OFFICE.

JAMES M. BROOKS, OF ATLANTA, GEORGIA.

CHURN.

Application filed August 20, 1928, Serial No. 300,733.

The object of this invention is to provide simple, easily-cleaned rotary mechanism for efficiently agitating the cream to quickly break up the fat globules therein and at the same time aerate the mass, to the end that a maximum of butter may be produced within a minimum of time, as more fully herein-after set forth.

In the drawing—

- 10 Fig. 1 is a vertical sectional view; and
Fig. 2 is a horizontal sectional view showing the churn of preferred construction;
Fig. 3 is a detail perspective view of the removable frame in the churn body.
15 Fig. 4 is a plan view of Fig. 3.

Referring to the drawing annexed by reference-characters, 5 designates a cylindrical vessel having a bottom 6 affixed within the same, this bottom being flanged at its 20 edge, where it is attached to the body 5, and being also curved downwardly, which structure gives rigidity to the churn body and renders it less likely to be injured by rough handling.

25 In the center of the bottom is formed a bearing for the lower end of the shaft 7 which carries a dasher generally designated by the numeral 8, at its lower end, and is attached by a removable coupling 9, at its 30 upper end, to a motor-driven shaft 10, this shaft 10 being adapted to be endwisely lifted in its bearing in order to disconnect the coupling 9, to thus permit the dasher-shaft and the attached parts to be removed from the 35 churn body for cleaning.

The dasher consists of a plurality of curved blades 11 having their lower edges curved to correspond with the concavity of the bottom 6 and being attached at their inner ends 40 to a hub 12 which is attached to the shaft 7. The outer edges of these blades 11 are connected together by a horizontal flat ring 13 whose outer edge is coincident with the outer edges of the blades 11, the center portion of 45 the ring being open to permit the milk to pass down into the cavity below the ring 13. On top of the ring 13 is a series of short vanes 14 which incline substantially in the same direction as the outer ends of the blades 50 11 and whose vertical edges terminate coincident with the edges of the ring 13.

In the bottom of the churn body, outside of the outer edges of the ring 13 and the blades 11 and 14, is affixed a series of vertical 55 ribs 15 which rise from the bottom 6 to a point about coincident with the top ends of

the vanes 14 and whose inner edges come close to the outer edge of the ring 13.

Mounted on the shaft 7 is a detachable frame consisting of a pair of separated transverse bars 16 having horizontal flat webs and a pair of vertical flat bars 17, the lower one of the bars 16 being arranged to connect the two vertical bars 17 at points between the ends thereof. The outer edges of the flat 60 bars 17 lie close to the inner surface of the churn body, and their outer ends rest upon the bottom 6 and abut flatwise against two of the diametrically-positioned ribs 15. This frame 16—17 is loosely mounted on the shaft 65 7 and, therefore, does not rotate with the same, but on the contrary remains stationary within the churn body, against rotation therein, by engagement with the ribs 15. It will be observed that when it is desired to 70 remove the parts for cleaning, it is simply necessary to disconnect the coupling 9 by raising the shaft 10, whereupon the shaft 7 may be lifted out of the churn together with all of the parts except the ribs 15, thus rendering it easy to clean the churn members. In operation, when the shaft 7 is operated rapidly, the milk will be thrown outwardly very forcibly into the pockets formed by the 75 ribs 15, and the centrifugal action imparted to the milk by means of the curved blades 18 and the inclined vanes or paddles 14 will give to the mass of milk a very rapid rotary motion, thus impacting it against the sides of the ribs 15. The milk will also have imparted to it an upward movement at the side 80 of the churn body, this being especially the result of the concaved shape of the bottom 6 and the ring 13, which together form a series of sort of nozzles which not only insure a 85 strong impact of the milk against the ribs in the side wall of the churn, but also give it an upward trend. The upwardly-moving, swirling mass of milk strikes against the flat sides of the bars 17 and also the flat sides and 90 flat top webs of the bars 16 and is thus further subjected to impacting force which assists in breaking up the fat globules. In practice, I have found that when the shaft 7 is rotated quite rapidly—say about 300 R. P. M.—the 95 centrifugal force set up by my dasher arrangement throws the upwardly-moving, swirling mass of milk so hard against the cylindrical wall of the churn body that a central open space is maintained in the body 100 of milk extending well down to the dasher and even to the bottom of the churn if the

churn is not overloaded with milk, thus indicating a very high degree of agitation, resulting in the production of butter within a minimum of time. With a speed equal to 5 that indicated above and operating on about five gallons of milk, I have succeeded in separating the butter fat from the milk within four minutes of the time of beginning the operation.

10 In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of 15 these may be altered and others omitted and some of the features of each modification may be embodied in the others without interfering with the more general results outlined, and the invention extends to such use.

15 I may attach a pulley 18 to the upper end of shaft 10 for the purpose of belting this shaft to an auxiliary apparatus such as an ice-cream freezer. I prefer to position the 20 lower one of the bars 16 close to the top edges of the blades 14 to thus increase the impacting effect of these blades. I prefer also to provide the bars 17 with inwardly-extending 25 paddles 19 for the same purpose.

30 What I claim as new is:

35 1. In a churn, the combination of a cylindrical body having an interiorly-concaved bottom and separated upright ribs at the juncture of the bottom and the vertical wall 40 of the body, a vertical rotary shaft within the body carrying a series of blades coincident with the aforesaid ribs and having their lower edges curved to conform to the concave bottom, said blades being connected together 45 at their outer edges by an open horizontal flat ring whose outer edge lies adjacent to the inner edges of said ribs.

50 2. In a churn, a cylindrical body having a bottom, a series of stationary separated radially-extending vertical ribs at the juncture

of the bottom and the body, a vertical rotary shaft having a dasher at its lower end consisting of curved blades terminating near the edges of said ribs and being connected at their upper edges by an open horizontal flat ring, 55 said ring being provided on its upper side with a plurality of inclined vanes.

3. In a churn, a cylindrical body having a bottom, a vertical rotary shaft carrying a dasher at its lower end adapted when rotated 60 to throw the milk outwardly against said body at the lower end thereof, short radial vertical ribs attached to the body outside of said dasher and opposite thereto, and a frame consisting of transverse bars having flat horizontal web portions and vertical bars loosely mounted on said shaft, said vertical bars being arranged close to the wall of the cylindrical body and having their lower ends in engagement with said ribs to prevent rotation of the frame.

4. In a churn, a cylindrical body having a bottom, a rotary shaft mounted therein and carrying a dasher at its lower end, this dasher consisting of blades and an open ring supported on the outer edges of said blades, the blades and said bottom being constructed to throw the milk outwardly and upwardly against the wall of the body, and a frame loosely mounted on the shaft and embodying 80 vertical side bars located adjacent to the inner face of the wall of the churn body.

5. In a churn, a cylindrical body having a bottom, a plurality of short radially-extending vertical ribs arranged around the body, 85 a vertical shaft having a dasher at its lower end positioned to rotate between the inner edges of said vertical ribs, the blades of the dasher being formed to throw the milk outwardly and against the sides of the vertical 90 ribs, and means mounted on the top edges of said dasher-blades at the outer ends thereof to direct the milk laterally between the vertical ribs and prevent its upward movement in the path of the outer ends of the 95 dasher-blades.

In testimony whereof I hereunto affix my signature.

JAMES M. BROOKS.
